ROAD MACHINE

Carl A. Gustafson, Minneapolis, Minn., assignor
to Caterpillar Tractor Co., San Leandro, Calif.,
a corporation of California

Application October 8, 1932, Serial No. 636,858

26 Claims. (Cl. 37—143)

This invention relates to road machines, and more particularly to cutting sections for grader blades. This application is a continuation in part of my application Serial No. 617,291, filed June 15, 1932, relating to Road machines.

In road machines having a grader blade adapted for a wide variety of uses such as plowing, cutting high-angle banks, etc., a great deal of cutting is done at the end of the moldboard. The provision of separate cutting sections, or end bits, which are adapted to be secured to the ends of the moldboard presents many advantages over the former practice of beveling the ends of the moldboard which are set forth fully in the application noted above. Various constructions of such end bits are known, all of which have a common disadvantageous feature, i. e., the respective bits of a pair are formed oppositely so that each can be applied only to one end of the moldboard. While working an end bit on a blade, the lower edge receives the greatest wear. Thus, the time of use of such an end bit without sharpening, and its total useful life, are determined by the lower cutting edge, and the end bit has to be sharpened or replaced while the side cutting edge is still effective. Another disadvantage is in the increased cost of manufacture of differently formed end bits for the two ends of the blade, and the larger number of end bits which the dealer has to carry in stock for replacements.

The present invention eliminates the above enumerated disadvantages by providing a reversible end bit which can be applied to either end of the moldboard. Thus the end bits at each end of the blade are interchangeable, and after the lower cutting edges, which receive the greatest wear are dulled, they may be interchanged so that new cutting edges are presented at the lower edge of the blade, while the cutting edges at the ends of the blade are still capable of effective work having received less wear. Thus the period of service of the blade as a whole is materially lengthened and the cost of upkeep of the machine is diminished. The cutting edges on the lower edge of the blade are also interchangeable so that each type of cutting section applied to the moldboard comprises interchangeable cutting sections.

The provision of interchangeable cutting sections is advantageous to the manufacturer and dealer as well as to the user. All cutting sections of a type being identically formed, a single process of manufacture can be used where two are otherwise necessary as, for example, when

the right end bit for application to the right end of a moldboard is formed differently from the left end bit. A smaller stock for replacement is also permissible with the interchangeable cutting sections.

It is an object of the invention to provide interchangeable cutting sections for grader blades.

Another object of the invention is to increase the efficient period of service of a grader blade.

Another object of the invention is to provide a cutting section which can be applied to either end of a grader blade.

Other objects will appear as the description progresses.

Description of figures

Fig. 1 is a front elevation of the blade of a road machine and also discloses the mounting means therefor.

Fig. 2 is a rear elevation of the blade.

Figs. 3—7 are views of the end bit applied to the right end of the blade.

Fig. 3 is a front elevation of the end bit applied to the blade.

Fig. 4 is a side elevation.

Fig. 5 is a fragmentary section taken on the line 5—5 in Fig. 3.

Fig. 6 is a fragmentary bottom view taken on the line 6—6 in Fig. 4.

Fig. 7 is a section taken on the line 7—7 in Fig. 4.

Description of device

The invention is disclosed as embodied in a grader, a portion of the main framework of which is shown at 25 in Fig. 1. The frame of the machine is suitably supported on wheels and axles, wheels 200 being the rear wheels of the vehicle. Said wheels 200 are rotatably mounted on bell cranks 228, 229 pivoted at 204, 205 in brackets 206, 207 secured to the ends of rear axle 208. The upwardly extending arms of cranks 228, 229 are interconnected by bar 230 which is shifted laterally to tilt the wheels.

Blade 300 (Fig. 1) consists of cutting edges 301 secured to moldboard 302 and end bit 600 secured to moldboard 302 and overlapping cutting edges 301. Angle bracket 305 (Figs. 1 and 2) is secured to moldboard 302 and angle 306 is secured to the trailing edge of angle 305. Brackets 309 are secured to angle bracket 305. Corresponding brackets 313 are secured to moldboard 302. Brackets 309, 313 are used for connecting the blade to the circle assembly in different positions.

Blade 300 is supported from circle 315 (Fig. 1).

the front half of which is encompassed by the central portion of beam 317 which is riveted thereto as disclosed in my said application. End portions 319, 320 of beam 317 extend tangentially from the circle and downwardly, their lower ends being apertured for connection to brackets 309 (Fig. 1) on angle 305 by means of pins 323. In order to rigidly connect the ends of the beam to the circle, brackets 325, 326 are riveted to end portions 319, 320, respectively. The upper ends of brackets 325, 326 are riveted to the ends of channel 327 which is rigidly connected to circle 315 by brackets. In addition, the lower end of brackets 325, 326 are rigidly secured by gussets 330, 331 to the lower ends of inclined braces 332, 333, the inner ends of which are riveted to channel 327.

The blade 300 is angularly adjustable about the axis of pins 323 to alter the inclination of cutting edges 301 to the surface of the ground. The blade is locked in adjusted position by links 335, one of which is shown in Fig. 1, which are pivoted at one end in brackets 313 on the moldboard and are secured adjacent the other end to clamping blocks 341 on the beam. A plurality of brackets 309, 313 is provided so that the blade may be connected to the beam in different transverse positions with respect to the surface so that the blade can be made to extend farther outwardly to the left or right of the machine as desired.

The circle is revolvably mounted in a framework consisting of forwardly converging side bars 342, 343 and rear cross bar 344. The rear end of side bar 342 is rigidly connected with the right end of bar 344 by bracket 345, being bolted to respective webs 346, 347 thereof. Similarly the rear end of side bar 343 is rigidly connected with the left end of bar 344 by bracket 348. Side bars 342, 343 converge forwardly and are connected at their front ends. The intermediate portions of the side bars are rigidly secured together by a casting which forms a front support for the circle. The inwardly extending flange of the circle rests on arcuate ledges 352 which are formed integrally with brackets 345, 348. Similar ledges are provided in the casting to support the front of the circle. The arcuate ledges provide a support for the circle on which the circle can be revolved and adjustable means are provided in the supports to take up wear in the parts and to reduce the amount of play between the circle and the support.

As disclosed in my aforesaid application, the circle supporting framework is connected by drawbars pivotally connected thereto and having a universal draft connection with the main frame. By reason of the pivotal connection between the drawbars and the circle supporting framework, the framework, together with the circle and blade, can be raised and lowered with respect to the drawbars, or, in other words, the angle between the drawbars and the plane of the circle can be varied. By reason of the universal draft connection between the drawbars and the main frame, the circle is capable of arcuate movement in horizontal and vertical planes about the pivotal center of the draft connection. As the drawbars are rotatably secured to the draft connection, the circle can be oscillated to vary the angle between the circle and the horizontal plane of the main frame. The desired circle adjustment is usually obtained by combinations of these movements.

Extensible lift arms are provided to connect the blade and circle assembly to the frame. The ends 75 of rear cross bar 344 (Fig. 1) of the circle sup-

porting framework are connected by ball and socket joints 400, 401 to links 402, 403 which telescope in links 404, 405 and which can be locked together in different positions to provide lift links of various lengths. Links 404, 405 are connected to lift arms on shafts mounted on the main frame. Means are provided for (1) shifting the center of the circle transversely of the machine, (2) shifting the circle on its own center, and (3) adjusting the plane of the circle with respect to the drawbars.

(1) For shifting the center of the circle, the supporting frame of the circle is adapted to be variously connected by a link to a rack on the main frame which can be slid transversely of the main frame. Rear cross bar 344 (Fig. 1) of the circle supporting framework is provided with apertures 500, 501 adjacent its ends for connection to a link 502 having a hooked end. The other end of link 502 is connected to the rack on the main frame. Movement of the rack causes link 502 to draw the circle supporting frame transversely and thereby shift the center of the circle.

(2) For shifting the circle on its center, it is provided with an arcuate rack 521 (Fig. 1) secured underneath the inwardly extending flange of circle 315. Rack 521 is engaged by a pinion which is operated in a manner disclosed in my said application to shift the circle about its center thereby varying the angle of cutting edges 301 with respect to the longitudinal axis of the circle supporting frame, or, in other words, with respect to the line of draft.

(3) For adjusting the plane of the circle with respect to the drawbars, adjustable connecting means are provided therebetween as fully disclosed in my said application. This adjustment serves to raise or lower the front end of the circle supporting frame. Such movement varies the angle of the cutting edges with respect to the surface of the ground when the blade is in its transverse position as illustrated in Fig. 1, and raises or lowers the front end of the blade if it is rotated from its transverse position. The lowering of the front end positions the blade to act as a breaker plow. In such operations the end bits are particularly valuable.

Blade and end bits

Moldboard 302 (Figs. 3 and 4) is arcuate in shape, the front face 302A (Figs. 4 and 5) being a portion of a cylindrical surface. The bottom edge of moldboard 302 is offset to provide a portion 302B to receive cutting sections 301 which have the same curvature as the moldboard. By this arrangement the front faces of moldboard 302 and cutting sections 301 provide an unbroken cylindrical surface which permits easy passage of earth without clogging. The longitudinal edges of cutting section 301 are bevelled at 301A and 301B (Fig. 5) the bevel 301A forming the cutting edge, and the bevel 301B serving to fit the cutting section into the offset of the moldboard without interrupting the cylindrical surface. Cutting sections 301 (Fig. 1) are removably attached to offset 302B by means of bolts 301C. The ends 302C (Fig. 7) of moldboard 302 are square, that is, their surface is normal to the cylindrical surface of the front face of the moldboard. The ends 301D (Fig. 6) of cutting sections 301 are also square and are flush with the ends 302C of the moldboard when assembled. As shown in Figs. 1 and 2, two cutting sections 301 are placed end to end at the bottom of the moldboard to provide the bottom cutting 75

edge of the blade. These cutting sections are substantially identical and are interchangeable, as shown by the symmetrical arrangement of bolts 301C in Fig. 2. They are also readily replaced by similar sections to maintain the efficiency of the lower cutting edge.

End bit 600 (Figs. 4 and 5) is formed with the same curvature as moldboard 302 and cutting section 301. Inner portion 601 (Figs. 5 and 7) has a rear surface 602 which contacts and conforms to the front face of the moldboard. Front surface 603 of inner portion 601 of end bit 600 is substantially parallel to rear surface 602, but unlike surface 602, it extends throughout the width of the end bit. Rear surface 602, on the other hand, terminates at square shoulder 604 on rib 605, which extends throughout the length of end bit 600 on its back. End bit 600 extends along the end of moldboard 302 and its bottom portion overlaps the outer end of cutting section 301. Shoulder 604 (Fig. 6) of rib 605 abuts end 302C of moldboard 302 and end 301D of cutting section 301. Square holes 617 (Figs. 5 and 7) are provided along the inner edge of end bit 600 and are countersunk at 607 for the reception of conical headed square-shanked bolts 606 which pass through aligned apertures in moldboard 302 to fasten end bit 600 in place thereon, bolts 606 being fitted with nuts 608.

The outer portion 609 (Fig. 7) of end bit 600 is thicker than inner portion 601, the rear surface 610 being spaced further from front surface 603 than rear surface 602. The cutting edge is formed by bevel 611.

The top and bottom edges of end bit 600 are similarly formed and only the bottom edge will be described in detail. Bevel 612 along the bottom edge of end bit 600 provides a continuation of the cutting edge of cutting section 301. An inspection of Figs. 4 to 6 will show that the lower corner of the blade is thus provided with a thicker, stronger cutting edge. This is a point in the blade where considerable wear takes place. Notice in Fig. 5 that the combined thickness of portion 601 of end bit 600 and of cutting section 301 is available for receiving extra stresses. Bevel 301A on cutting section 301 and bevel 612 on portion 601 of end bit 600 cooperate at this point to form a cutting edge which is stronger and more durable than the cutting edge of section 301 alone. Beyond the end of section 301, end bit 600 (Figs. 4 and 6) is made thicker in portion 609 and is provided with a bevel 615 on the rear face, which bevel is substantially parallel to bevel 301A as shown in Fig. 4. The lower outside corner of end bit 600 is cut off at 614 (Fig. 3) which is the line of intersection of bevels 611 and 612 to make a more durable point and one less apt to break off than a square corner. Bevel 613 along the inner edge of end bit 600 provides a smooth surface for passage of earth over the end bit and moldboard. Bottom bolt 606 (Fig. 5) passes through end bit 600, cutting section 301 and offset portion 302B of moldboard 302.

The top edge of end bit 600 (Fig. 3) is provided with bevel 612A which, when said end bit is applied to the left end of the moldboard (to the right as viewed in Fig. 1) provides a continuation of the cutting edge of cutting section 301. The top edge of end bit 600 has bevel 615A (Fig. 4) on its rear face which is similar to bevel 615 on the bottom edge. The top outside corner of end bit 600 is cut off at 614A similarly to the lower outside corner at 614. In Figs. 1 and 2 the end

bit shown on the left end of the moldboard has the reference numerals applied thereto as though the end bit shown on the right end had been removed and placed on the left end, the top and bottom edges being reversed. Thus it is seen that the moldboard has a station at each end to which the end bit can be applied.

It is to be noted that in both positions of the end bit, rib 605 protects the ends of moldboard 302 and cutting section 301; positions end bit 600 thereon, prevents the end bit from working loose, and transmits end thrusts and twisting strains on the end bit directly to the moldboard, thereby relieving bolts 606 from strains tending to break or wear the bolts loose.

Thus it is seen that the end bits, as well as the cutting sections, are interchangeable, and if an end bit is changed from one end of the moldboard to the other new cutting surfaces are provided at the place in the substantially continuous cutting edge which receives a substantial portion of the wear. This substantially continuous cutting edge comprises (referring to Figs. 1 and 2) 611, 614, 612 and 615, 612 and 301A together, 301A, 301A and 612A together, 612A and 615A, 614A and 611.

I, therefore, claim as my invention:

1. A scraper blade end bit formed integrally and having an even concave front face and a convex back face having a longitudinal apertured blade engaging portion, a second thicker longitudinal portion, and a longitudinal rib intermediate said portions having a blade engaging face, said blade engaging portion having a bevelled edge, said second portion having a bevelled cutting edge, the ends of said end bit being bevelled on the concave face thereof and on the convex face adjacent said second portion.

2. A scraper blade end bit formed integrally and having an even concave front face and a convex back face, a longitudinal apertured blade engaging portion having a radius of curvature substantially equal to the radius of curvature of the blade, and a second thicker longitudinal portion having a blade engaging edge, said end bit having cutting edges on three sides thereof.

3. A cutting section for grader blades having a concave front face and a convex back face adapted to fit flush against a complementary curved face of the grader blade, all the edges thereof being bevelled and lying substantially in the same arcuate surface.

4. A cutting section for grader blades having substantially parallel opposite bevelled faces, a stiffening rib intermediate said faces and parallel thereto, and third and fourth bevelled faces on opposite edges of said cutting section and substantially normal to said first named faces.

5. A cutting section for grader blades having substantially parallel opposite bevelled faces, and third and fourth bevelled faces on opposite edges of said cutting section and substantially normal to said first named faces.

6. In a road machine, an adjustably supported blade comprising a moldboard, cutting sections secured thereto, and end bits secured to said moldboard and overlapping said cutting sections, said end bits being interchangeable.

7. In a road machine, an adjustably supported blade comprising a moldboard, cutting sections secured thereto, and end bits secured to said moldboard and overlapping said cutting sections, said end bits being interchangeable and said cutting sections being interchangeable.

8. In a road machine, an adjustably supported

- blade comprising a moldboard and a cutting section adapted to be secured to either end thereof, said cutting section being shaped to lie substantially in and continue the surface of said moldboard, a face of said cutting section conforming to the configuration of said moldboard and adapted to engage flush against said moldboard, and another face of said cutting section being substantially normal to said first-mentioned face and 10 adapted to engage against an end of said moldboard.
9. The combination with a moldboard of an end bit having cutting edges on three sides thereof and shaped to lie substantially in and continue 15 the surface of said moldboard, a moldboard engaging face extending from the fourth side thereof and adapted to engage flush against said moldboard at either end thereof, and another moldboard engaging face adapted to engage flush 20 against either end of said moldboard.
10. A scraper blade end bit shaped to be secured to said scraper blade so as to lie substantially in and continue the surface of said scraper blade when secured thereto, said end bit having cutting edges at opposite ends thereof, and being adapted to be secured at either end of said 25 scraper blade so that either of said end cutting edges can be disposed in operative cutting position to cooperate with the lower edge of said scraper 30 blade depending upon the end of the scraper blade to which the end bit is secured.
11. A scraper blade end bit shaped to be secured to said scraper blade at either end thereof, and to lie substantially in and continue the 35 surface of said scraper blade when secured thereto, the shape of said end bit being such that the projection thereof on a flat planar surface forms a rectangle, opposite ends of said end bit being parallel and providing cutting edges each adapted 40 to be disposed in operative cutting position to cooperate with the lower edge of said scraper blade depending upon the end of the scraper blade to which the end bit is secured, and a third cutting edge on said end bit disposed at right angles to said parallel cutting edges and adapted 45 to lie beyond either end of said scraper blade.
12. A scraper blade end bit formed integrally and shaped to be secured to said scraper blade so as to lie substantially in and continue the surface 50 of said scraper blade when secured thereto, said end bit having cutting edges at opposite ends thereof, and being adapted to be secured at either end of said scraper blade so that either of said end cutting edges can be disposed in operative cutting position to cooperate with the lower edge of said scraper blade depending upon the end of the scraper blade to which the end bit is secured, and a face extending between said cutting edges and adapted to engage either end 55 of said scraper blade.
13. A scraper blade end bit formed integrally and shaped to be secured to said scraper blade so as to lie substantially in and continue the surface of said scraper blade when secured thereto, said end bit having cutting edges at opposite ends thereof, and being adapted to be secured at either end of said scraper blade so that either of said end cutting edges can be disposed in operative cutting position to cooperate with the lower edge of said scraper blade depending upon the end of the scraper blade to which the end bit is secured, a rib extending between said cutting edges and adapted to engage either end of said scraper blade, and a third cutting edge on said 65 bit extending between said first-mentioned cutting edges and adapted to lie beyond either end of said scraper blade.
14. A scraper blade end bit formed integrally and shaped to be secured to said scraper blade so as to lie substantially in and continue the surface of said scraper blade when secured thereto, said end bit having cutting edges at opposite ends thereof, and being adapted to be secured at either end of said scraper blade so that either of said end cutting edges can be disposed in operative cutting position to cooperate with the lower edge of said scraper blade depending upon the end of the scraper blade to which the end bit is secured, a third cutting edge on said bit extending between said first-mentioned cutting edges and adapted to lie beyond either end of said scraper blade, and a fourth beveled edge on said bit also extending between said first-mentioned cutting edges and adapted to lie always within the ends of said 70 scraper blade.
15. In a device of the class described, a scraper blade comprising a moldboard, cutting means secured thereto and adapted to provide a lower cutting edge, the cutting means and moldboard being shaped to provide a substantially even surface, and end bits secured to said scraper blade and overlapping said cutting means, each end bit being of such shape that the projection thereof on a flat planar surface forms a rectangle, said end bits being interchangeable, opposite ends of 75 each of said end bits being parallel to provide cutting edges each adapted to be disposed in operative cutting position to cooperate with said lower cutting edge depending upon the end of the scraper blade to which each end bit is secured.
16. In a device of the class described, a scraper blade comprising a moldboard, cutting means secured thereto and adapted to provide a lower cutting edge, the cutting means and moldboard being shaped to provide a substantially even surface, and end bits secured to said scraper blade and overlapping said cutting means, each end bit being of such shape that the projection thereof on a flat planar surface forms a rectangle, said end bits being interchangeable, opposite ends of 80 each of said end bits being parallel to provide cutting edges each adapted to be disposed in operative cutting position to cooperate with said lower cutting edge depending upon the end of the scraper blade to which each end bit is secured, and fastening means including a member passing through each end bit, the cutting means and the moldboard for securing the end bits.
17. A scraper blade end bit having a front face and a back face providing a blade-engaging portion, a second thicker portion, and a rib intermediate said portions and having a face adapted to engage an end of the scraper blade, said second portion having a beveled cutting edge, the ends of said bit being beveled on the front face thereof and on the back face thereof adjacent said second portion.
18. A scraper blade end bit having a front face and a back face providing a blade-engaging portion, and a second thicker portion adapted to lie beyond an end of said scraper blade, said second portion having a cutting edge, the ends of said bit being beveled on the front face thereof and on the back face thereof adjacent said second portion.
19. A scraper blade end bit having a front face and a back face providing a blade-engaging portion, and a second thicker portion adapted to lie beyond an end of said scraper blade, said 90

blade-engaging portion having a beveled edge, said second portion having a beveled cutting edge, the ends of said end bit being beveled on the front face thereof and on the back face adjacent said second portion.

20. In a device of the class described, a scraper blade, and an end bit having upper and lower cutting edges adapting the end bit to be secured in operative position to either end of said scraper blade, said end bit being shaped to lie substantially in and continue the surface of said scraper blade and having a face conforming to the configuration of said scraper blade, said face being adapted to overlap and engage flush against said scraper blade, said scraper blade having a plurality of apertures extending between the top and bottom thereof at each end, and said end bit having similarly disposed apertures extending between the upper and lower cutting edges, all the apertures being adapted to receive fastening members therethrough to hold the end bit rigidly flush against the scraper blade along the entire area of said scraper blade overlapping said end bit.

21. In a device of the class described, an arcuately shaped scraper blade, and an end bit having a complementary arcuate shape, and upper and lower cutting edges formed on said end bit adapting said end bit to be secured in operative position at either end of said scraper blade with a portion of the back face of said end bit lying flush in overlapping relationship against a portion of the front face of said scraper blade, said scraper blade having a plurality of apertures extending between the top and bottom thereof at each end, the apertures being symmetrically arranged with respect to the center line of said scraper blade extending between the ends thereof, and said end bit having similarly disposed apertures extending between the upper and lower cutting edges, all the apertures being adapted to receive fastening members therethrough to hold the end bit rigidly flush against the scraper blade along the entire area of said scraper blade overlapping said end bit.

22. In a device of the class described, a scraper blade, an end bit detachably secured to each end of said scraper blade in overlapping relationship with respect thereto, each end bit being shaped to conform to the configuration of said scraper blade so as to lie substantially in and continue the surface of said scraper blade, and means for adapting said end bits for interchangeability, comprising upper and lower cutting edges on each end bit, and a plurality of fasteners holding each end bit flush against the scraper blade along the entire overlapping areas thereof.

23. In a device of the class described, a scraper

blade, an end bit detachably secured to each end of said scraper blade in overlapping relationship with respect thereto, each end bit being shaped to conform to the configuration of said scraper blade so as to lie substantially in and continue the surface of said scraper blade, and means for adapting said end bits for interchangeability, comprising upper and lower cutting edges on each end bit, and a plurality of fasteners holding each end bit flush against the scraper blade along the entire overlapping areas thereof, said fasteners being symmetrically disposed with respect to the center line of said scraper blade extending between the ends thereof.

24. In a device of the class described, a scraper blade, an end bit at each end of said scraper blade in overlapping relationship with respect thereto, said end bits each having an upper cutting edge and a lower cutting edge to adapt said end bits for interchangeability, and means for detachably securing said end bits with the entire overlapping areas of the end bits and scraper blade in rigid contact.

25. A scraper blade end bit shaped to be secured to said scraper blade so as to lie flush thereagainst and provide an extension which is of substantially the same transverse configuration as the transverse configuration of said scraper blade when secured thereto, said end bit having cutting edges at opposite ends thereof and being adapted to be secured at either end of said scraper blade so that either of said cutting edges can be disposed in operative cutting position to cooperate with the lower edge of said scraper blade depending upon the end of the scraper blade to which the end bit is secured.

26. In a device of the class described, an arcuately shaped scraper blade, and an end bit having a complementary arcuate shape, and upper and lower cutting edges formed on said end bit adapting said end bit to be secured in operative position at either end of said scraper blade with a portion of the back face of said end bit lying flush in overlapping relationship against a portion of the front face of said scraper blade, said scraper blade having a plurality of fastening stations extending between the top and bottom thereof at each end, the stations being symmetrically arranged with respect to the center line of said scraper blade extending between the ends thereof, and said end bit having similarly disposed fastening stations extending between the upper and lower cutting edges, all the fastening stations being adapted to cooperate with fastening means to hold the end bit rigidly flush against the scraper blade along the entire area of said scraper blade overlapping said end bit.

CARL A. GUSTAFSON.
